Thomas Conley
INVENTOR
BY
Victor J. Evans
ATTORNEY

J. A. Wynn
WITNESS:

UNITED STATES PATENT OFFICE

THOMAS CONLEY, OF WEST NEWTON, MASSACHUSETTS

WINDOW SCREEN

Application filed October 18, 1926. Serial No. 142,406.

This invention relates to a screen for a window and the like, the general object of the invention being to provide improved means whereby the screen is constructed wholly of metal and can be manufactured to sell at low cost.

Another object of the invention is to provide means whereby the wire mesh can be easily renewed when worn.

10 This invention also consists in certain other features of construction and in the combination and arrangement of the several parts, to be hereinafter fully described, illustrated in the accompanying drawings and specifically 15 pointed out in the appended claims.

In describing my invention in detail, reference will be had to the accompanying drawings wherein like characters denote like or corresponding parts throughout the several 20 views, and in which:—

Figure 1 is a view showing the screen in a window.

Figure 2 is an edge view of the improved screen.

25 Figure 3 is a transverse sectional view through the screen.

Figure 4 is a view of a bar from which one of the sections of the screen frame is made.

Figure 5 is a view showing how the meeting 30 ends of the bar are connected together.

As shown in these views, the frame A of the screen is formed of the two sections 1 and 2. Each section is formed of a bar of metal, such as shown at 3 in Figure 4, with V-shaped 35 notches 4 cut at intervals therein, after which the bar is bent at these notches to form a rectangular figure, as shown in Figure 1. The ends of the bar are mitered, as shown at 5, and overlapped and fastened together by a 40 rivet or the like. The wire mesh B is placed between the two sections and then the two sections fastened together, with the wire mesh between them, by means of the screws 6 which engage holes 7 formed in the sections.

45 Thus a screen of considerable strength is produced, the parts of which are all of metal and when the wire mesh is to be renewed, the frame sections can be taken apart by removing the screws with a screw driver or the like, 50 removing the old mesh and substituting the

new mesh. Then the screws are put back to cause the sections to clamp the mesh between them.

It is thought from the foregoing description that the advantages and novel features 55 of my invention will be readily apparent.

I desire it to be understood that I may make changes in the construction and in the combination and arrangement of the several parts, provided that such changes fall within the 60 scope of the appended claim.

What I claim is:—

A window screen comprising a pair of similarly shaped sections formed of flat stock with the flat face of one section adapted to be 65 placed on the flat face of the other section, each section being formed from a bar provided with three notches, with the bar bent at the notches to form a rectangular frame, with the ends of the bar mitered and fastened 70 together, screen mesh having its edges placed between the two sections, one section having threaded holes therein and the other section having plain holes therein registering with the threaded holes when the sections are 75 placed together and screws passing through the holes.

In testimony whereof I affix my signature
THOMAS CONLEY.
